ADVERTISING CARD HOLDER

Filed May 10, 1929

INVENTOR
WILLIAM AUBERLIN
BY *John A. Bonnahatt*
ATTORNEY

UNITED STATES PATENT OFFICE

WILLIAM AUBERLIN, OF NORTHFIELD, OHIO

ADVERTISING-CARD HOLDER

Application filed May 10, 1929. Serial No. 361,915.

This invention relates to card holders and particularly to card holders of the type which are used in stores for holding advertising cards.

5 An object of the invention is to provide an advertising card holder which can be fastened to a wall or to a shelf or in a show window.

Another object is to provide a card, picture or sign holder embodying two spring 10 clamps whereby cards can be quickly and easily removed or replaced when desired.

Other objects and advantages will be seen when taken in connection with the accompanying drawings in which Fig. 1 is a plan 15 view of the card holder; Fig. 2 is a sectional view of one of the spring clamps; Fig. 3 is a cross section on the line 3—3 of Fig. 1; Fig. 4 is a section on the line 4—4 of Fig. 1; Fig. 5 is a perspective view of the device; Fig. 20 6 is a perspective of a modification.

In the drawings in which like numerals indicate similar parts 6 indicates the base of the card holder which is an elongated metallic strip, with bent side edges forming 25 strengthening flanges. Adjacent or near each end of the base plate is a recessed portion indicated at 7. These recesses 7 provide for the reception of two spring clamping members 8. Slots 9 are cut in the top of the base 30 plate 6 so as to allow the middle portion of the plate or the portion extending between the two slots to be depressed thus forming a seat or groove to accommodate the metal rod 10 extending practically the whole length of the base plate 6. The spring clamps 8 are soldered or otherwise rigidly secured to the rod 10 at the cut out portions 7. It will be seen that the rod 10 is frictionally engaged 35 between the raised portions 11 and the depressed portion 12. This allows the rod 10 to turn with friction for the adjustment of the spring clamping members to various desired positions, from vertical to practically horizontal.

45 In the modification shown in Fig. 6 the

base plate 6 has cut therein at each end two slots 13 and 14 which allow the portions 15 to be struck up and the portion 16 to be depressed thus forming a channel or groove to receive the rod 10, in frictional contact with the struck up and depressed portions. In this form of the invention the spring clamping members are arranged to accommodate diamond shaped cards or signs. The clamping members are rigidly secured to the upper 50 ends of the arms 17 the lower ends of the arms being securely fastened as by soldering or welding to the rod 10 at the point 18.

It may be stated that at the ends of the base plate 6, holes 19 are provided for the 55 reception of nails, screws or other fastening means whereby the device can be securely fastened to a shelf or the like.

Holes 20 in the spring clamping members 8 permit the use of a fastening clip or pin 60 whereby the card or sign may be securely fastened in the clamping members. Necessity for this fastening means arises only in case the card or sign is unusually large in which case the spring tension of the clamps 65 may not be sufficient to hold the card.

It will thus be seen that a very efficient, 70 cheap and useful advertising card holder is produced which is adapted to hold a card in various positions ranging from practically 75 horizontal to vertical.

I claim:

1. In an advertising card holder the combination of an elongated strip having recesses near each end and a longitudinal depression in the strip, a rod extending along the strip in said depression, and spring clamps fixed to said rod in said recesses, the rod being frictionally held in said depression whereby it may be turned to various positions 80 85

2. In a card holder, a base having spaced recesses therein disposed adjacent each end and further having slits between the recesses, said base being further provided with a longitudinal groove in its upper face extending 90

between the slits, a rocking rod seated in said groove and extending through the slits and across the recesses, and card holding clamps mounted on said rod at said recesses.

- 5 3. A card holder comprising an elongated strip having a longitudinal groove pressed therein and slits at each end of the said groove, a rocking rod seated in the groove and extending through said slits, whereby it may be turned to various angles, and clips secured on said rod.

10 In testimony whereof I do affix my signature.

WILLIAM AUBERLIN.
